Application May 29, 1934, Serial No. 728,138

17 Claims. (Cl. 196—13)

This invention relates to improved methods and means for fractionating hydrocarbon oils by means of solvents and it pertains more particularly to the fractionation of lubricating oil stocks into paraffinic oils, naphthenic oils and asphalts, the last two being sometimes withdrawn as a single fraction.

An object of our invention is to minimize solvent requirements and to minimize solvent losses. A further object is to provide apparatus which can be built and operated at a minimum expense. A further object is to provide a system which will give maximum yields of oils of good color, low carbon residue, resistance to oxidation, 15 sludging, and high viscosity index, or, in other words, which will insure a sharp separation between desirable paraffinic fractions and less desirable naphthenic fractions. A further object is to provide a combined deasphalting and solvent extraction system wherein the optimum temperatures and optimum proportions of oil to solvents will be employed in every stage throughout the entire system. A further object is to use the heat from a high temperature propane deasphalting stage to flash propane from an intermediate raffinate prior to its introduction to the following stage. Also, our object is to remove propane from stage to stage as we approach the admission of fresh solvent into the system and to effect a temperature increase simultaneous with this removal of propane. A further object is to return depropanized oils from an extract treating system to a solvent extraction system at a point above the main oil feed, 30 so that the added oil will be of about the same paraffinicity as the oil in the system. Other objects will be apparent as the detailed description of our invention proceeds.

Our invention relates primarily to the use of at least two different solvents, one of them preferentially dissolving naphthenic oil components and the other dissolving paraffinic oils and rejecting color bodies and high molecular weight asphaltic compounds. The solvent for dissolving naphthenic components may be phenol, cresol (cresylic acids, ortho, meta, para and mixtures thereof), coal tar and wood tar acids usually associated with phenol and/or cresol, pyridine, furfural, nitrobenzene, aniline, chloraniline, benzaldehyde, benzonitrile, chlorophenol, nitrotoluene, phenyl acetate, dichlorethyl ether, sulfur dioxide, etc. and/or mixtures of one or more of any of these compounds. Our other solvent is preferably a light hydrocarbon such as ethane, propane, butane, isobutane, pentane,

hexane, with perhaps some propylene, butylene, etc. or mixtures of one or more of said hydrocarbons. Such hydrocarbons or mixtures thereof (except hexane and perhaps pentane) may generally be described as liquefied normally gaseous 5 hydrocarbons and for our purposes they should usually have a vapor pressure between those of propane and butane. It should be understood, however, that we do not limit ourselves to the use of light hydrocarbons as supplementary solvents to the solvents for extracting naphthenic components. We prefer to use propane, but we may employ any light solvents which are equivalent to the propane in its property of precipitating asphalt and treating paraffinic oil out of 10 extract material.

Our invention is based on the results of a vast amount of research which has established certain fundamental principles that were heretofore not known and our invention resides in the 20 utilization of these fundamental principles and their application in practical solvent refining processes and apparatus.

More specifically, we have found that propane can be used to precipitate asphalt from an asphalt-bearing oil, that the propane precipitates the extremely high molecular weight components of the oil whether naphthenic or paraffinic, and that at high temperatures of from about 140° to 200° F. the deasphalting action of propane is 25 sufficient to remove a large portion of the color bodies to yield an oil of extremely low carbon residue or Conradson carbon and one which requires a very small amount (if any) of clay for 30 finishing. By "high temperatures" we mean temperatures within about 50° or 60° F. of the critical temperature of the light hydrocarbon solvent (propane, butane, ethane, etc.).

We have found that many of the popular notions as to the virtue of propane in countercurrent extraction processes are in error; particularly we have found that propane is undesirable in that portion of a solvent extraction process wherein the fresh solvent is introduced and the final raffinate is withdrawn; if propane is permitted to remain in the system at these points, an unduly large amount of the naphthenic solvent will be required, which in turn means that solvent losses will be greater and that equipment costs will be greater, and at the same time fractionation is not as sharp as when propane is removed from the system.

We have found that propane may be used to excellent advantage to throw paraffinic oil out of solvent-extract mixtures, particularly when 55

the oil stock is extremely naphthenic (Gulf or West Coast oils).

In practicing our invention we preferably subject asphalt-bearing residuum to a countercurrent propane-deasphalting step, the oil being first deasphalting at temperatures between 100 to 200° F. to remove practically all of the coloring matter and carbon-forming bodies from the paraffinic and naphthenic oils. The rejected layer from the first stage is again propane-deasphalting with fresh propane at a lower temperature to recover the valuable oils which were thrown out with the asphalt in the first stage and this recovered oil is then returned to said first stage. The light colored oil from the initial deasphalting stage is flashed to remove a substantial portion, if not all, of the propane and the depropanized light colored oil is then countercurrently extracted with the naphthenic solvent.

The extract from the countercurrent extraction of the deasphalting oil is treated with propane, preferably in the presence of solvent, and the paraffinic oil which is recovered from the extract is returned to the main countercurrent extraction system and preferably at a point above the main oil inlet.

Our invention is capable of many modifications; it may be used on any type of oil whether distillate or residue, no matter what its source, viscosity, or chemical characteristics. It may also be used on synthetic oils, oils obtained from shale and from brown coal tars, oils produced by hydrogenation and, in fact, any mixture of paraffinic and naphthenic oil components.

The invention will be more fully understood from the following drawings which form a part of this specification, in which similar parts are designated by like reference characters throughout the several views and in which:

Figure 1 is a miscibility diagram of a three-component solvent extraction system: oil, propane and anhydrous cresylic acid; the oil in this case is a distillate having a viscosity of 105 seconds, Saybolt universal, at 210° F. and made from Mid-Continent crude;

Figure 2 is a miscibility graph showing effect of varying amounts of propane on miscibility temperature of a 50:50 mixture of said oil and anhydrous cresylic acid (vertical section on line $zebmP$ of Figure 1);

Figure 3 is a flow diagram showing a preferred outline of our process;

Figure 4 is a flow diagram to represent high temperature propane treating and deasphalting at an intermediate stage with counter-current extraction of depropanized asphalt-free oil;

Figure 5 is a flow diagram to represent a multi-stage counter-current system with increasing temperatures of propane treating and deasphalting followed by increasing but lower temperatures of counter-current extraction in the presence of diminished amounts of propane; and

Figure 6 diagrammatically represents another embodiment of our invention wherein the deasphalting and treating of the extract are carried out in separate systems.

It will be noted that Figures 3, 4 and 6 represent the process as carried out in continuous countercurrent towers or horizontal extractors wherein the solvent flows through the system in one direction and the oil flows through in the opposite direction. Figure 5 represents a multi-stage system wherein the solvent and oil are mixed and settled to form intermediate extracts

and/or raffinates which are in turn mixed with raffinates from prior stages or extracts from later stages, respectively. It should be understood, of course, that for the purposes of our invention we contemplate the use of multi-stage batch countercurrent apparatus in the systems of Figures 2, 3 and 5 where such apparatus offers sufficient advantages in temperature control, pressure control, phase separation, etc.

Three-component systems

It will be noted that in certain stages of our process we must consider the mutual effect on each other of the three components; oil (including paraffinic, naphthenic and sometimes asphalt), solvent, and light hydrocarbon. In our preferred example we will discuss the case of an S. A. E. 50, Mid-Continent distillate (105 seconds Saybolt universal viscosity at 210° F.) extracted with anhydrous cresylic acid wherein propane is used as a deasphalting agent. A three-component chart of such a system is shown in the triangular diagram of Figure 1. Point X represents 100% cresylic acid; point Y, 100% oil; and point P, 100% propane. Points along the line YX represent ratios of oil to cresylic acid in the absence of propane; along YP represent the proportion of propane to oil in the absence of cresylic acid; and along XP represent cresylic acid to propane in the absence of oil. Any point within the triangle represents a three-component system, the fraction for any component being the ratio of the length of the perpendicular line from the point under consideration to the boundary opposite the apex for that component, divided by the altitude of the triangle. Thus, point k represents a mixture of 50% oil, 30% propane and 20% cresylic acid.

This mixture of components may be in one, two or three separate liquid phases depending upon the proportions of various components and the temperature of and pressure on the mixture. Our solvent extraction process depends on the presence of two liquid phases although a separate asphalt phase may sometimes be present as a part of the extract. In the study of this problem we have determined innumerable miscibility temperatures,—those temperatures at which the system changes from one to two liquid phases and vice versa with slight alteration of temperature. Thus the miscibility temperature of point k may be 30° F., of point m may be 80° F., of points r may be 100° F., of point t may be 120° F., etc.

After obtaining this mass of information concerning miscibility temperatures, we connected all points having an equal miscibility temperature and for 80° F. we obtained lines abc and lmn . We find that all components falling under the shaded areas bounded by these lines form two separate phases at temperatures at or below 80° F. while the unshaded areas of the triangles represent three-component systems which are entirely miscible at temperatures of 80° and even lower.

Next we connect points representing miscibility temperatures of 100° and obtained curves def and qrs respectively. All double shaded areas under these lines form two phases at or below 100° and points outside of the double shaded areas are entirely miscible at temperatures of 100° and even lower.

We have found that the shaded areas represent systems having miscibility temperatures higher than 80° F. and that the miscibility temperatures increase toward the sides of the triangle which form one boundary of the shaded

area. If we are considering a mixture containing equal parts of oil and cresylic acid with varying amounts of propane or, in other words, if we travel along the line $zebmP$ we find that as more and more propane is added the miscibility temperatures first decrease then increase and finally decrease again. This is clearly brought out by Figure 2.

It is usually desirable to operate solvent extraction processes at or slightly above room temperatures,—about 80° to 100° F. Lower temperatures require expensive refrigeration and are complicated by wax separation, while higher temperatures result in undesirable and unnecessary heat losses. If only a small amount of propane is added to any composition in shaded area abc (Figure 1), the resulting composition will be displaced toward P or, in other words, it will result in a decrease in miscibility temperature, which is undesirable. This fact is shown more clearly in Figure 2 wherein the same points are represented by the same letters and wherein "percent propane" is plotted against miscibility temperature. If propane is added anywhere to the left of w or w' , the miscibility temperature is lowered, but if it is added between points w and r —the miscibility temperature is increased or in other words phase separation is favored.

When very large amounts of cresylic acid are used, particularly with naphthenic oils, the miscibility temperature of the mixture becomes so low that phase separation in the absence of propane is impossible at temperatures of 80 – 100° F. For instance, point a in Figure 1 represents a mixture of which the miscibility temperature is just 80° F. If propane is added to this mixture, the miscibility temperature of the three-component system will be as illustrated by the dashed line, from which it will be seen that at least 35% propane is necessary to effect phase separation at temperatures higher than 80° F., optimum operating mixtures containing from 50–80% of propane. The use of propane is most desirable here because it gives very high miscibility temperatures.

In practice we do not employ as much as 97 parts cresylic acid to 3 parts of oil, but we have discovered that naphthenic oils have the same effect as additional amounts of cresylic acid in lowering the miscibility temperature. In other words, the cresylic acid-extract produced in our extraction process may be entirely miscible at 80° F. in any proportion and it will exhibit the characteristics of the dashed-line curve in Figure 2 at higher concentrations of oil than shown for the dashed line in Figure 2. To obtain further phase separation for recovering additional paraffinic oil from this extract, it is necessary to add a considerable amount of propane to the mixture to throw the composition in the double cross-hatched area.

Cresylic acid raffinate, on the other hand, will correspond more nearly to the conditions shown by the dotted lines or the dot-dash lines of Figures 1 and 2. In this case it will be seen that the maximum miscibility temperature and, therefore, maximum phase separation will be obtained in the absence of propane. No amount of propane will throw the miscibility temperature of a 6:4 oil-cresol mixture in the desired operating range on the right hand side of Figure 2.

In extracting any given crude with any given solvent, we have found that an amount of propane should be used which will give the highest miscibility temperature with the minimum required

amount of solvent. This amount of propane may be determined by making preliminary experiments to obtain curves corresponding to those shown in Figures 1 and 2 and then regulating the amount of propane in each stage of the extraction process to obtain the maximum miscibility temperature in that stage. The optimum amount of solvent is usually about 1 to 3 parts per part of oil. In the final raffinate stages propane should be absent. Enough propane should be employed in the remaining stages to shift the composition of the mixture to the region of maximum miscibility temperatures, as indicated by the double cross-hatched area in Figure 2.

The elimination of propane from paraffinic raffinate stages not only increases the miscibility temperature and brings about greater yields of high pour point oil, but it decreases remarkably the proportion of solvent which is necessary to obtain a given yield and viscosity index. This decrease in the amount of necessary solvent decreases the cost of original equipment, the cost of operating expense and most important of all it decreases the unavoidable loss of solvent in the recovery of it from resulting extracts and raffinates.

While still on the subject of the miscibility diagram, we should point out that this diagram is not the same for all crudes and that the naphthenic components of a crude behave much the same way in a system as the cresylic acid as far as miscibility is concerned. If a solvent concentration is increased beyond a certain point the miscibility temperature is lowered; likewise if the proportion of naphthenic materials in the oil is increased beyond a certain point the miscibility temperature is lowered. The addition of propane is desirable in the first stages of the countercurrent extraction of the raffinate whenever the propane tends to increase the miscibility temperature because this promotes phase separation. It is desirable to remove the propane or at least a large portion of it before the final contacting of raffinate with fresh solvent because this final raffinate will be paraffinic in character.

Deasphalting—Solvent extraction

In Figure 3 we have shown how the phenomena of propane deasphalting can be utilized with great effectiveness in our solvent extraction system. Oil feed from line 10 is deasphalting in the single stage unit 11 by means of propane which is introduced through lines 12 and 13. The propane introduced through line 12 contains paraffinic oil which has been removed from the extract in countercurrent system 14, the propane being introduced thereto through pipe 15 and extract removed therefrom through pipe 16. The propane which is introduced into the deasphalting unit through pipe 13 carries with it the propane-soluble oils from countercurrent deasphalting system 17 to which propane is introduced through line 18 and from which asphalt is removed through line 19. In this manner all of the good oils from both the asphalt and the extract are recovered and the propane which is associated with these oils is utilized in deasphalting incoming feed stock.

The propane-soluble oil from unit 11 is introduced through line 20 to propane still 21 wherein it is substantially depropanized and then passed by line 22 to countercurrent or multi-stage raffinate solvent extraction system 23. Solvent is introduced through line 24 and raffinate with-

drawn through line 25. The solvent-extract mixture is transferred by line 26 to the countercurrent extract treating system 14. The asphalt from unit 11 is transferred to countercurrent asphalt washing system 17, the asphalt finally being removed through line 19. It should be understood throughout this description that there may be propane and/or solvent in the streams leaving the system, both of which are to be recovered and re-used in accordance with well known practice.

An outstanding feature of this system is the recovery of good (paraffinic) oil from both the extract and the asphalt and the depropanizing of the raffinate to prevent the presence of the propane in the countercurrent raffinate extraction system. Another feature of this process is the double use of propane for washing purposes in countercurrent systems 14 and 17 and for deasphalting in unit 11. It should be understood, however, that we may introduce the oil from line 12 directly into the countercurrent raffinate system, but in this case we prefer to remove propane therefrom, at least in the final stages of the raffinate extraction system. Other modifications and expedients will be more clearly understood from the following more detailed description.

Elevated temperature intermediate stage

The use of propane for deasphalting is well known ("Use of Propane in Lubricating Oil Refining" presented before American Petroleum Institute October 25, 1933, by Bray, Swift and Carr). It has also been discovered that oil may be fractionated by means of propane at increased temperatures and pressures. A black oil may be soluble in propane at 80°, but when this propane solution is heated under pressure to 150° a phase separation occurs, the black color bodies and asphaltic constituents forming a lower phase and a lower molecular weight paraffinic oil forming the upper phase. As this temperature increases to the critical temperature of propane, the black oil phase increases in volume and the propane phase becomes lighter and lighter in color, the oil remaining dissolved in the propane gradually assuming a lower viscosity, a lower carbon residue or Conradson carbon, and a lighter color. We may utilize this phenomenon in our solvent extraction system in two ways: We may employ the high temperature deasphalting step as a part of a countercurrent deasphalting process prior to the solvent extraction, so that asphalt and color bodies will not contaminate the solvent extraction system, increase the difficulty of solvent recovery and/or increase the cost of claying or finishing of the final lubricant. When asphaltic material does find its way into a countercurrent solvent extraction system and propane is used to wash the good (paraffinic) oil out of the extract we utilize the high temperature deasphalting in the presence of the solvent to throw out objectionable color bodies and asphaltic materials and to thereby obtain the same advantages as those hereinabove indicated. In both cases we may utilize the heat which is stored in the propane-oil mixture by the high temperature deasphalting step to distill the propane from the oil prior to the introduction of said oil into the solvent extraction system.

An example of the use of our high temperature propane wash at an intermediate stage is diagrammatically illustrated in Figure 4. Here the deasphalting and treating of the extract is accomplished in the same apparatus, which appa-

ratus is designed to withstand pressures of from 500 to 1000 lbs. per square inch. The oil is introduced through line 10 to pressure vessel 28 which is provided with a steam coil 29 or other heating means. The heating means may, of course, be dispensed with if the incoming oil is of a sufficiently high temperature so that the resulting mixture will be at about 140° to 200° F. It will be observed that in this arrangement the deasphalting is accomplished simultaneously with the treating of the extract, so that line 26 leads directly from countercurrent system 23 to the hot propane precipitation pressure vessel 28 (which corresponds to single stage unit 11 of Figure 3) and asphaltic material together with solvents from pressure vessel 28 are conducted by pipe 27 to the countercurrent extract washing system 14. Since the intermediate stage is at high pressure we use a pump 30 in line 26, pressure release valve 31 in line 20, a pump 32 in line 12, a pressure release valve 33 in line 27 and in addition we employ a cooler 34 in line 27, so that undue pressures will not be built up in the countercurrent washing system 14. We may, however, operate the propane washing stages or the entire system under the same pressure that prevails in high temperature stage 28. We prefer to maintain a temperature of about 140° to 200° F. in pressure vessel 28 while we prefer to operate countercurrent raffinate system 23 and countercurrent extract system 14 at lower temperatures. It will be noted that although a cooler 34 is employed in line 27, such a cooler is not necessary in line 20 because the heat in the paraffinic oil-propane solution is used to distil or flash off the propane in still 21, so that the depropanized oil entering the raffinate extraction system through pipe 22 is not only substantially free of propane, but it is also at the desired operating temperature. In fact the heat of the solution may not be sufficient for propane removal and we may employ steam coils in depropanizer 21, bringing the depropanized oil back to about 70-80° F. by means of a suitable cooler.

To describe briefly the operation of the apparatus shown in Figure 4, the propane with its good (paraffinic) oil from treating system 14 is passed countercurrent to the extract from extraction system 23. System 28 is at so high a temperature and pressure (it may be called a "pressure vessel") that there is no appreciable phase separation between paraffinic and naphthenic constituents of the type illustrated in Figure 1, but there is a separation between the paraffinic-naphthenic solutions and the asphaltic and color bodies which may have been carried from the extract system with the oil solution in line 12. Thus the propane-soluble fraction which leaves pressure vessel 28 through line 20 is light colored and relatively free from asphalt and carbon-forming substance and when it is depropanized in still 21 and extracted in raffinate system 23 an excellent raffinate is obtained from line 25. At the same time a large amount of good (paraffinic) oil is thrown out of solution in pressure vessel 28 and this good oil is recovered in the lower temperature countercurrent propane washing system 14.

We prefer to introduce the incoming feed stock directly into pressure vessel 28, so that as much propane-soluble oil as possible may be introduced directly into the raffinate countercurrent system 23, thereby placing a smaller burden on countercurrent extract washing system 14 and making that system more efficient. It should be under-

stood, however, that the incoming oil may be introduced at one of the later stages of the extract treating system 14 or one of the earlier stages of the raffinate countercurrent system 23.

5 Also, while we have shown the removal of propane at one point in still 21, it should be understood that the propane may be removed at a later point in the countercurrent raffinate system or it may be reduced progressively as the oil progresses through said raffinate system toward the introduction of fresh solvent.

As hereinabove stated, we will probably prefer to carry out our process in a continuous multi-stage countercurrent apparatus as diagrammatically illustrated in Figure 5. The process illustrated by this figure is fundamentally the same as that shown in Figure 4 and it may be described as follows:

Oil stock from line 10 is admixed with extract 20 from a raffinate countercurrent system (from line 35) and raffinate from an extract countercurrent system (from line 36) and this entire mixture is introduced into high pressure separator 37 at a temperature of about 180° F. The various liquids 25 may be mixed in suitable mixers and if necessary they may be passed through a heat exchanger 38 to bring them up to the required temperature. The extract layer from separator 37 is withdrawn through line 39 and admixed with raffinate withdrawn 30 from a preceding settler through pipe 40, the mixture being introduced at an intermediate point of settler 41. This settler is preferably at a lower temperature, about 130° to 140° F., and the temperature of the settler may be controlled 35 by means of the heat exchanger 42. Raffinate from settler 41 is that which was hereinabove described as being withdrawn through line 36 for admixture with incoming oil stock. Extract from settler 41 is withdrawn through line 43 and admixed 40 with incoming propane from line 44, the mixture being effected in a mixing apparatus 45 designed to admit the propane in small amounts and with sufficient agitation to prevent agglomeration of asphaltic materials. This mixture of 45 propane with extract is introduced into settler 46 and final extract and asphalt are withdrawn therefrom through pipe 47. Settler 46 is preferably maintained at above room temperature and pump 48 may therefore be necessary to force 50 raffinate from settler 46 through line 40 to settler 41. Likewise, pump 49 may be required to force raffinate from settler 41 through line 36 to the higher temperature settler 37. A pressure reducing valve 50 may be employed in line 55 39 and a pressure reducing valve 51 in line 43. The entire system may be operated at a uniform high pressure. It will thus be seen that in the countercurrent extract washing stages (which also act as deasphalting stages) there is a constant decrease in temperature from the entrance 60 of the oil stock to the withdrawal of the extract.

In the upper part or raffinate countercurrent section the temperatures are lowered sufficiently to effect phase separation. In this case the lowering of the temperature may be brought about in part by vaporization of propane. Thus the raffinate from settler 37 is passed through pressure releasing valve 52 to propane still 53 and propane is removed through line 54 to a suitable recovery system. The depropanized oil from line 55 is admixed with a solvent extract mixture from pipe 56 and this mixture is introduced at the central part of settler 57 which is preferably maintained at a temperature of about 70° F. It 70 may be maintained at this temperature by steam 75

coils in the settler, but preferably by heat exchanger 58 through which the incoming materials are passed.

Extract from settler 57 is forced by pump 59 through line 35 as hereinabove described. Raffinate from settler 57 is withdrawn through line 60 admixed with a solvent extract from line 61 and the mixture introduced into the center of settler 62 preferably at about 80° F. If there is any propane in the raffinate which is withdrawn in line 60, it may be removed by still 63 and the depropanized raffinate may be mixed with extract 61 as hereinabove described. Here again the temperature of the fluids entering the system may be regulated by heat exchanger 64. Extract from settler 62 is passed by pipe 56 to settler 57 as hereinabove described.

Finally, the raffinate from settler 62 is passed by line 65 to be admixed with incoming solvent through line 66, this mixture being settled in 20 settler 67 at about 90° F. Any remaining propane may be removed by by-passing the raffinate in line 65 through still 68. Extract from settler 67 is withdrawn through line 61 and raffinate is withdrawn from the system through line 69. 25

It may be desirable to gradually increase the temperature of the countercurrent raffinate extraction system, in which case the heat means employed in stills 63 and 68 may furnish the necessary heat for increasing the temperatures 30 of the final raffinate settling systems. However, our invention is not limited to a temperature variation in this part of the system except insofar as said temperature regulation is tied up with the removal of propane from the raffinate 35 streams. It will be understood, of course, that the lubricating oil stock may be introduced at a point nearer the extract end of the system or nearer the raffinate end of the system depending upon the nature of the stock introduced, but 40 as a general rule it is more desirable to introduce it at the high temperature stage.

The embodiment shown in Figure 5 contemplates the deasphalting and the treating of the residue in the same system, but if there is a large 45 amount of asphalt in the oil stock we prefer to accomplish the deasphalting in a separate stage prior to the introduction of the oil into the apparatus described in Figures 4 and 5. In such cases a large amount of the propane necessary 50 for the high temperature propane precipitation step may be introduced with the paraffinic-naphthenic oil mixture from the deasphalting step and the asphalt may be recovered separate and distinct from the extract as shown in Figure 3. 55

Separate asphalt recovery

As indicated in Figure 3 we prefer to remove the asphalt and the naphthenic oil in separate streams and our preferred embodiment is therefore indicated in Figure 6. The incoming oil from line 10 meets a propane solution from line 70 and the mixture is introduced into a high temperature high pressure vessel 71. This vessel corresponds to vessel 28 of Figure 4 and it 60 may be heated by steam coil or the entering liquids may be passed through a heat exchanger. The exact temperature maintained in this vessel will depend somewhat on the nature of the oil undergoing treatment, but it should be sufficient to throw out all asphaltic materials and 65 objectionable color bodies.

The precipitated oils and asphalt are withdrawn from pressure vessel 71 through line 72, pressure reducing valve 73 and cooler 74, after 70 75

which they are mixed with another propane solution from line 75 and the mixture is introduced into deasphalting chamber 76. The raffinate from chamber 76 is forced by pump 77 through pipe 78 as hereinabove described. The extract from chamber 76 is withdrawn through pipe 78, mixed with propane from line 79, and introduced into deasphalting chamber 80. Asphalt is removed from the system through line 81 and the propane-soluble material from chamber 80 is returned to the preceding stage through line 75 as hereinabove described.

The light colored propane-soluble oil from the top of pressure vessel 71 is withdrawn through line 82 and pressure reducing valve 83 to propane still 84 and the depropanized oil is introduced by line 75 to countercurrent raffinate extraction system 23.

The extract from the raffinate extraction system is withdrawn through line 86, mixed with a propane solution from line 87 and introduced into propane washing chamber 88. Since the extract is naphthenic in character and since there is a preponderance of solvent, the addition of the propane solution tends to promote further phase separation, so that much valuable paraffinic oil is removed from the solvent and extract material (note Figure 1 and above discussion thereof). The extract from the base of chamber 88 is withdrawn through pipe 89, mixed with propane solution in pipe 90, and introduced into settling chamber 91. The raffinate from settling chamber 91 is passed by line 87 for admixture with incoming extract as hereinabove described. The extract from settler 91 is withdrawn through line 92 and mixed with fresh incoming propane through line 93, the mixture being settled in chamber 94. Raffinate from chamber 94 is withdrawn through pipe 90 for admixture with prior extract material as hereinabove described. Naphthenic oil is removed from the system through line 95.

The propane solution of paraffinic materials which have been recovered from the extract is withdrawn from the top of settler 88 by pipe 96, depropanized in still 97, and passed by pipe 98 to that portion of tower 93 in which the liquids have a corresponding paraffinic character, usually considerably higher in the tower than the introduction of deasphalting naphthenic charging stock.

We may avoid the necessity of depropanizing still 97 by passing the propane solution from settler 88 directly through pipe 99 by means of pump 100 to high pressure deasphalting vessel 71. The propane thus introduced may facilitate the deasphalting step by supplying added amounts of propane and the slight amount of solvent which is carried into the deasphalting step therewith may likewise facilitate phase separation and the removal of undesirable constituents. It should be noted that when line 99 is employed Figure 6 is substantially the same as Figure 3, but in both of these cases it becomes necessary to remove solvent from the asphalt stream as well as from the naphthenic oil stream. Ordinarily, therefore, we prefer to return the propane solution from settler 88 directly back to the raffinate extraction system. This offers the further advantage that the oil may be introduced into said tower at a point of corresponding paraffinicity.

In Figures 1 and 2 we have shown curves relating to S. A. E. 50 MC distillate, anhydrous cresylic acid and propane. Other oil stocks, sol-

vents, and light hydrocarbons may be used in place of those hereinabove described. In such cases the curves will not be of exactly the shape as those shown in Figures 1 and 2, but they will be of the same general character—they will show that light hydrocarbons like ethane and propane tend to promote phase separation in mixtures which are largely naphthenic, and tend to promote miscibility in mixtures which are more paraffinic. The presence of small amounts of water (about 2%) in the cresylic acid greatly increases the tendency toward phase separation. Alcohols and other modifiers may also be added for this purpose. Also mixed solvents including a halogenated solvent may be more effective than single solvents in color removal. In any case, however, the desirability or undesirability of propane will follow the general rule hereinabove stated.

In Figures 4, 5 and 6 we have shown the use of different pressures in the various propane washing stages, but it should be understood that the entire system may be designed to operate under pressures of 350 to 2000 pounds per square inch.

In all of the systems hereinabove described the paraffinic oil has been separated from the extract in the presence of the solvent. We may, of course, distil the solvent from the extract and then admix the extract with incoming oil or we may subject the extract to a propane fractionation at high temperature or to a subsequent fractionation with different solvents either to produce an intermediate grade lubricating oil or to produce additional paraffinic materials for introduction into the main raffinate extraction system.

In the above description we have not attempted to describe all of the necessary pumps, valves, storage tanks, propane and solvent recovery systems, etc. Such features are well known to those skilled in the art and their illustration on the drawings would tend to confuse rather than clarify the invention. It should be understood, however, that we contemplated the use of pressure and temperature control devices, mixers, heat exchange features, etc. in accordance with sound engineering practice.

As hereinabove stated, an outstanding feature of our invention is the regulation of the amount of propane present in various parts of the system in order to obtain the desired miscibility temperatures and a sharp fractionation of paraffinic and naphthenic components. A further feature is the employment of a sufficiently high temperature to cause the separation of an asphalt phase in an intermediate section even though the paraffinic and naphthenic oils are miscible with each other. A further feature is the improved interrelation of our deasphalting and extraction systems, so that each may function with maximum efficiency and contribute to the obtaining of maximum yields of high viscosity index lubricating oils. A further feature is the utilization of the heat from a high temperature deasphalting step to remove propane prior to solvent extraction.

We claim:

1. The method of refining a petroleum lubricating oil stock containing asphaltic, naphthenic and paraffinic components which comprises treating said oil stock with propane at a temperature of about 140 to 200° F. to separate asphaltic components from a propane solution of naphthenic and paraffinic components, treating the asphaltic components with additional pro-

pane at a lower temperature to recover propane-soluble oils therefrom, returning said propane-soluble oils together with propane to the high temperature propane treating step whereby the recovered propane-soluble oils are combined with propane-soluble naphthenic and paraffinic components separated in the first step, removing propane from the paraffinic and naphthenic components, and separating the paraffinic from the naphthenic components by means of a naphthenic oil solvent.

2. The method of claim 1 wherein the separation of the naphthenic from paraffinic components is effected countercurrently.

3. The method of claim 1 wherein the naphthenic component is further treated with propane and wherein the propane-soluble material therefrom is admixed with the hot propane solution of naphthenic and paraffinic components from the high temperature separation step.

4. The method of refining a lubricating oil stock containing asphaltic, naphthenic and paraffinic components which comprises admixing said stock with a propane solution of material extracted from asphaltic components, effecting a phase separation of said oil-propane mixture at a temperature of about 140 to 200° F. to separate asphaltic components from the propane solution of paraffinic and naphthenic components, treating said asphaltic components with propane to obtain the solution for the first step of the process, removing propane from the mixture of naphthenic and paraffinic components, and cooling the mixture to a temperature of about 70 to 100° F., countercurrently extracting said mixture with a naphthenic solvent, and separately recovering asphaltic components, naphthenic components, and paraffinic components from admixtures of the same with propane and naphthenic solvents.

5. The process of claim 4 wherein the naphthenic components from the solvent extraction step are treated with propane and wherein the propane solution from said treatment is admixed with the propane solution of paraffinic and naphthenic components prior to the removal of propane therefrom.

6. The method of refining a lubricating oil stock containing paraffinic, naphthenic and asphaltic components which comprises treating said stock with propane at a temperature of about 140 to 200° F., removing propane from the mixture of paraffinic and naphthenic components, countercurrently extracting said depropanized mixture with a preferentially naphthenic solvent to yield a paraffinic component and an extract, countercurrently treating said extract with propane to yield a naphthenic component and a propane-oil solution, countercurrently treating said asphaltic component with propane to yield another propane-oil solution, and admixing both of said oil and propane solutions with incoming oil stock for said propane treatment thereof at about 140 to 200° F.

7. The method of refining a lubricating oil stock which comprises admixing said stock with propane, heating said mixture to a temperature of 140 to 200° F. under pressure sufficient to maintain the propane in liquefied condition whereby a propane phase and a heavy oil phase are formed, treating said heavy oil with propane at lower temperatures and returning said propane with propane-soluble material to the higher temperature higher pressure fractionation step, removing propane from the propane-oil solution formed in the high temperature high pressure step, and

simultaneously lowering the temperature of said oil to about 70 to 100° F., and extracting said oil with a preferentially naphthenic solvent.

8. The method of claim 7 wherein the naphthenic solvent from the solvent extraction step is introduced into said high temperature high pressure propane treating step.

9. The method of refining a lubricating oil stock containing asphaltic, naphthenic and paraffinic components which comprises mixing said stock with a light hydrocarbon which has been used to recover paraffinic oils from mixtures thereof with other materials, subjecting said light hydrocarbon solution and oil stock to a temperature within about 60° F. of the critical temperature of the light hydrocarbon under a pressure sufficient to maintain the light hydrocarbon in liquid phase whereby two liquid phases are formed, separating the lighter liquid phase from the heavier liquid phase at said temperature, separating the paraffinic from the naphthenic components in at least one of said liquid phases by means of a naphthenic solvent in a plurality of stages, and using different proportions of light hydrocarbon diluent in said stages for obtaining phase separation in said stages.

10. The method of refining a lubricating oil stock containing naphthenic, paraffinic and asphaltic components which comprises treating said oil stock with propane at a temperature of about 140-200° F. and at a pressure sufficient to maintain the propane in liquid state whereby a propane-soluble fraction is separated from a propane-insoluble fraction, treating the propane-insoluble fraction with further amounts of propane at lower temperatures to recover propane-soluble fractions therefrom, returning said propane-soluble fractions to said first-named step, reducing the pressure on the propane-soluble fractions from the first-named step whereby propane is removed from the solution and the temperature of the solution is lowered to below 100° F., countercurrently extracting the cooled depropanized solution with a naphthenic solvent to form a raffinate and an extract, treating said extract with propane to increase the miscibility temperature of the oil-solvent mixture and cause further separation of paraffinic oil in propane solution, removing propane from said solution, introducing said depropanized solution to said countercurrent extraction system, and removing propane from the asphalt, raffinate and extract and removing solvents from the raffinate and extract.

11. The combination of claim 10 wherein the depropanized solution from the treating of the extract is introduced into the counter-current solvent extraction system at a point at which its paraffinicity is the same as the paraffinicity of the raffinate in said system.

12. The method of refining mineral lubricating oil stocks which comprises introducing said stock into a high temperature zone maintained at a temperature of at least 140° F. and a pressure sufficient to keep propane liquid at said temperature, introducing a selective solvent into an extraction zone, introducing extract solvent solution from the extraction zone to the high temperature zone, introducing propane into said high temperature zone, removing paraffinic material from said high temperature zone to a depropanizing zone and from said depropanizing zone to said extraction zone, removing raffinate from said extraction zone and removing solvent-extract solution from the high temperature zone.

13. The method of claim 12 wherein the solvent

comprises a phenolic liquid of the class consisting of phenols, cresols, cresylic acid, and coal tar and wood tar acids associated with phenol.

14. The method of refining lubricating oil stocks which comprises extracting said stocks with about 1 to 3 volumes of a selective naphthenic solvent, introducing propane into the extract end of the system between the point at which the oil is introduced and the point at which 5 extract is removed, whereby the miscibility temperature of the solvent-extract mixture is modified to release paraffinic oil, maintaining the oil-propane-solvent mixture at a temperature of at least about 140° F. and a pressure sufficient 10 to keep the propane in the liquid phase at the point of oil introduction, maintaining lower temperatures in the raffinate and extract ends of the system, respectively and removing propane from the raffinate end of the system between the point 15 of introduction of said lubricating oil stock and the point of introduction of the selective solvent, whereby the miscibility temperature is again altered to cause liberation of paraffinic oil from the solvent and to cause solution of naphthenic material therein.

15. The method of refining mineral lubricating oil stock containing asphaltic, naphthenic and paraffinic components, which comprises introducing said stock into a high temperature propane 20 treating zone at a pressure sufficient to keep the propane in a liquid state, introducing a selective solvent into an extraction zone, transferring solvent-extract solution from the extraction zone to a propane treating zone at a lower 25 temperature than the first-named propane treating zone, introducing propane into said low temperature treating zone and removing solvent-extract material therefrom, transferring propane solution from said lower temperature propane 30 treating zone to said high temperature treating zone to furnish the propane therefor, removing 35

paraffinic material from said high temperature zone to a depropanizing zone and from said depropanizing zone to said extraction zone, and removing raffinate from said extraction zone.

16. The method of refining a lubricating oil 5 stock containing asphaltic, naphthenic and paraffinic constituents which comprises introducing said stock into a high temperature propane treating zone for separation of asphaltic components, transferring the asphaltic components 10 to a lower temperature propane treating zone and introducing propane into said zone for recovering paraffinic and naphthenic components from said asphaltic components, withdrawing asphalt from said lower temperature zone, 15 introducing the propane solution from the lower to the high temperature propane treating zone to furnish propane therefor, transferring the propane solution from the high temperature zone to a depropanizing zone and utilizing the sensible 20 heat of the solution to furnish the latent heat of evaporation of propane whereby the depropanized solution is cooled to about 70° F. to 100° F., extracting said depropanized solution with a 25 selective solvent in proportions to effect separation of naphthenic from paraffinic components at said temperatures of about 70° F. to 100° F., and separately removing asphalt, raffinate and extract from the system.

17. The method of claim 16 which also includes 30 the steps of transferring the extract solution from the solvent extraction zone to a propane treating zone, adding propane to said material in said zone for dissolving paraffinic material from the extract, removing extract solution from said, 35 propane-treating zone, depropanizing the solution of paraffinic components and returning said paraffinic components to said extraction zone.
